UNITED STATES PATENT OFFICE.

JOSEPH H. HOADLEY, OF NEW YORK, N. Y.

FLUID-PRESSURE MOTOR.

SPECIFICATION forming part of Letters Patent No. 586,384, dated July 13, 1897.

Application filed May 7, 1896. Serial No. 590,559. (No model.)

To all whom it may concern:

Be it known that I, JOSEPH H. HOADLEY, a citizen of the United States, residing at New York, in the county and State of New York, 5 have invented certain new and useful Improvements in Fluid-Pressure Motors, of which the following is a specification.

My invention relates to improvements in the reversing mechanism for fluid-pressure 10 motors; and it consists, essentially, of operating the reversing mechanism by a fluid-pressure-operated device under the control of the mechanism which opens and closes the throttle-valve.

15 My invention is particularly applicable to the link-reversing mechanism in which the reversing-link is attached to a rod extending from a piston which works in the fluid-pressure cylinder communicating at its opposite 20 ends with a fluid-pressure pipe or reservoir and a suitable exhaust. The communication between the cylinder and the reservoir and exhaust is controlled by a suitable valve attached to and operated by the handle which 25 opens and closes the throttle-valve of the engine.

The accompanying drawing represents a sectional elevation of a fluid-pressure motor embodying my invention.

30 A is the engine-cylinder.

B is the piston, and C the piston-rod.

D is the sliding cross-head, to which the piston-rod C is attached and which slides in the ways E.

35 F is the crank-shaft, carrying the crank G, which is connected to cross-head D by the rod H. The crank G works in the crank-pit I.

b' are inlet and exhaust ports in the cylinder A.

40 K is the main supply-port, and L is the main exhaust-port.

M is the compressed-air or fluid-pressure supply-pipe.

N is the throttle-valve cylinder, communicating with air-pipe M and with the main supply-port K through the pipe O.

45 P is a throttle-valve comprising the main central piston p and the two end pistons p' p'', all of which are maintained on the valve-rod 50 p'', which extends through a suitable packing-box in the head of the valve-cylinder and is

pivoted to the bell-crank-operating hand-lever Q.

R is the cut-off valve, comprising, preferably, two simple D slide-valves r r', mounted 55 upon a rod r'.

S is the reversing-link, having its end pivoted to the rods S' S'', carrying the eccentric-yokes s' s'' at their ends, which operate upon the eccentrics t and t', keyed to the crank-shaft F.

U is the bearing-block, mounted upon the outer end of the rod r', upon which the link S slides vertically.

V is the fluid-pressure reversing-cylinder, 65 having passages v' and v'' extending from its opposite ends to the valve-cylinder V', which is attached to or forms a continuation of the throttle-valve cylinder N.

V' is the piston, working in the cylinder V' 70 and carrying the piston-rod V'', which is pivotally attached to the link S. The valve-cylinder V' communicates through the port v'' with the air-pipe M and with the open air through exhaust v'.

75 W is a slide-valve supported in valve-cylinder V' and adapted to be operated by a collar w, which is mounted upon a continuation of the valve-rod p'', which extends from the valve-cylinder N into the valve-cylinder V'. 80

By means of the apparatus just described I am enabled to reverse the direction of the engine by the movement of the handle which opens the throttle-valve. In the intermediate position of the valves (shown in the drawing) 85 the throttle-valve will be closed and one port of the reversing-cylinder V will be in open communication with the air-pipe while the other port will be closed, so that the reversing mechanism will not be moved. By the 90 movement of the lever Q for opening the throttle-valve the reversing mechanism will be shifted to one position or the other for running the engine in the desired direction.

Having thus described my invention, what 95 I claim as new, and desire to secure by Letters Patent, is—

1. The combination, in a fluid-pressure engine or motor, of suitable reversing mechanism, a fluid-pressure-operated device controlling the reversing mechanism, a fluid-supply pipe communicating with the engine or mo-

- tor and the reversing controlling device, a throttle-valve in the supply-pipe controlling the supply of fluid to the motor, a valve controlling the supply of fluid to the reversing 5 controlling device, and a suitable engine-controlling device constructed to simultaneously operate the throttle-valve and valve of the fluid-pressure-controlling device of the reversing mechanism.
- 10 2. The combination, in a fluid-pressure engine or motor, of the reversing mechanism, a fluid-pressure cylinder, a piston working in the cylinder and connected with the revers-

ing mechanism of the engine, a valve controlling the admission and exhaust to and 15 from the fluid-cylinder, the fluid-pressure-supply pipe communicating with the engine or motor and with the reversing fluid-cylinder, the main throttle-valve of the motor, and a single controlling device constructed to operate both valves simultaneously, substantially as set forth.

JOSEPH H. HOADLEY.
